UNITED STATES PATENT OFFICE.

ISAAC HURLEY, OF ONTARIO CENTER, NEW YORK.

MOTOR.

1,081,044.

Specification of Letters Patent.

Patented Dec. 9, 1913.

Application filed March 29, 1913. Serial No. 757,633.

To all whom it may concern:

Be it known that I, ISAAC HURLEY, a citizen of the United States, residing at Ontario Center, in the county of Wayne and State of New York, have invented certain new and useful Improvements in Motors, of which the following is a specification, reference being had to the accompanying drawings.

10 This invention relates to new and useful improvements in wave, tide and current motors.

An object of this invention is the provision of a motor such as described, which 15 will be operated through the medium of the waves and tides, and currents of rivers and smaller streams.

Another object of this invention is the provision of a wave, tide and current motor 20 for which will adjust itself to the direction of the tides and winds.

A further object of this invention is the provision of a motor such as described, in which the water wheels can be adjusted to 25 suit the depth of the water.

A still further object of this invention is the provision of a motor such as described, which will be comparatively simple and inexpensive to manufacture, reliable and efficient in use and readily operated.

With the above and other objects in view, this invention resides in the novel features of construction, formations, combinations and arrangements of parts to be hereinafter 35 more fully described, claimed and illustrated in the accompanying drawings, in which—

Figure 1 is a side elevation of my invention; Fig. 2 is an end view thereof; Fig. 3 40 is a transverse sectional view thereof, taken on the line 3—3 of Fig. 1; Fig. 4 is a diagrammatic view showing the water gate; Fig. 5 is a view of the device used as a current motor for rivers or smaller streams; 45 and Fig. 6 is a similar view showing the same supported by a float.

Referring to the accompanying drawings by similar characters of reference throughout the several views, the numeral 10 designates generally my improved current motor.

11 shows a support which is preferably of substantially cylindrical formation, provided at its upper end with a track 12 in 55 which are disposed the wheels 13, which support a rotary bed or platform 14. Upon

this platform 14 is secured a framework or housing 16 which is disposed above the apparatus protecting it from the weather. A plurality of spaced supporting plates or frames 17 are slidable within slots in the platform 14, upon the opposite sides of the support 11, and in spaced relation thereto, these said plates or frames 17, in other words, being arranged in pairs upon the 60 opposite sides of the support 11.

Horizontal shafts 18 are journaled in each pair of plates or frames 17 and have keyed thereto between the plates, water wheels 19, each of which consists of end members 20 70 connected by the customary blades 21. The shafts 18 have further secured thereto gear wheels 22, which mesh with the gear wheels 23 carried by an operating shaft 24 journaled in the frames 17 and having the ends 75 slidably engaged in the slots in the guide plates 25. This shaft 24 has further keyed thereon adjacent its ends sprocket wheels 26 which extend through slots in the platform 14. These sprocket wheels 26 are connected by chains to the sprocket wheels 27 80 keyed to the shafts 28 of the drums 29 mounted upon the platform 14 at the opposite sides thereof. These drums are operatively connected by cables 30 to any suitable transmission mechanism located upon the shore, and not shown in the drawings.

As shown in the accompanying drawings, the upper ends of the plates 17 are slidably connected to the platform 14 and secured 90 to the outer of these plates 17 at the opposite sides thereof are flexible connecting members 31 which are attached to drums 32 carried by shafts 33 mounted upon the platform. These shafts are operated by the 95 means of crank arms 34 which constitute a means for raising and lowering the wheels 19 to suit the depth of the water. These shafts 32 are locked against retrograde movement by ratchets 35 and engaging 100 pawls 36, thereby retaining the wheels in their adjusted positions.

As shown more particularly in Fig. 5 of the drawings, a modified form of wheel is illustrated in which the shaft 24 is mounted 105 upon the opposite banks of a narrow stream. In this form, the remainder of the mechanism is substantially the same as that in Figs. 1 to 3 inclusive.

Fig. 6 illustrates a still further modification of the invention in which the wheels 19 are carried by a float 37 anchored to the

banks of the stream by cables 38. In this form, the gear wheels 22 are secured to the inner sides of the wheels 19 which are provided with internal teeth for engagement 5 with the gear wheels 23. The remainder of the mechanism, however, is substantially the same as shown in the remainder of the figures.

Fig. 4 shows a pair of gates 37 mounted 10 in advance of the wheels 19, which are operated by the racks 38 and pinions 39 to swing the gates in advance of the wheel to limit the passage of water therethrough.

From the foregoing disclosures, it will be 15 manifest that a wave, tide and current motor is provided which will fulfil all of the necessary requirements of such a device.

To prevent separation of the support 11 and the platform 14, a plurality of pending arms 40 are detachably connected 20 to the under face of the platform, the lower ends of the arms being offset inwardly, as at 41. An annular ring 42 is detachably connected to the periphery of the support 25 11, the offset extremities 41 of the arms 40 being adapted to engage under the ring, whereby separation of the motor mechanism from the support is prevented. It will be understood that the wheels 19 may 30 be raised entirely out of the water by rotation of the crank arms 34, or one of the wheels may be raised out of the water by rotation of one of the crank arms to transmit less power to the motor mechanism. It 35 should be understood in this connection that various minor changes in the specific details of construction can be resorted to within the scope of the appended claims without departing from or sacrificing any of the advantages of the invention.

Having thus fully described this invention, what I claim as new and desire to protect by Letters Patent is:—

1. In a motor of the type described, the combination with a support, of a platform carried by the support and having spaced openings, a shaft journaled upon said platform, plates slidably engaged in the openings of the platform, means secured to the shaft and engaged around the lower ends 45 of the plates for raising and lowering the same through said openings, an operating shaft mounted in the upper ends of the plates, means for guiding the opposite ends of the operating shaft, water wheels mounted 50 between the lower ends of the plates, gears connecting the operating shaft and the water wheels, drums mounted upon the platform, connections between the operating shaft and the drums, and means for transmitting power from the drums.

2. In a motor of the type described, the combination with a support, a platform carried by the support, a shaft journaled upon said platform, plates slidably supported by 55 the platform, flexible connecting members secured to the plates and shaft, an operating shaft, gears connecting the operating shaft and water wheels, drums mounted upon the platform, a connection between 70 the operating shaft and the drums and means for transmitting power from the drums.

In testimony whereof I hereunto affix my signature in the presence of two witnesses. 75

ISAAC HURLEY.

Witnesses:

WM. CUNNINGHAM,
PETER VAN HANELEM.
